US0D1054913S

(12) **United States Design Patent** (10) **Patent No.:** **US D1,054,913 S**
(45) **Date of Patent:** **** Dec. 24, 2024**

(54) **DRONE**

- (71) Applicant: **Zihua Xu**, Shantou (CN)
(72) Inventor: **Zihua Xu**, Shantou (CN)
(**) Term: **15 Years**
(21) Appl. No.: **29/955,762**
(22) Filed: **Aug. 3, 2024**
(51) LOC (14) Cl. **12-06**
(52) U.S. Cl. **USPC .....** **D12/16.1**
(58) **Field of Classification Search**
